SEALING DEVICE

Charles E. Evans, Council Bluffs, Iowa, assignor
of one-fourth to L. G. Howard, Council Bluffs,
Iowa

Application November 11, 1936, Serial No. 110,293

3 Claims. (Cl. 215—56)

This invention relates to sealing devices generally and particularly to sealing devices for vacuum sealing of containers and the like.

It has been found in canning foods and the like that same may be better preserved by exhausting the air from the container in which said foods are preserved. To produce satisfactory results in canning foods it is highly desirable to use simple means for sealing the container and such means should be adapted for quick and easy removal in opening the containers after same have been sealed. In exhausting the air from the container any suitable vacuum pump mechanism may be used.

It is therefore an important object of my invention to provide sealing means of this character whereby air may be exhausted from the container.

Another object of my invention is to provide a device of this character whereby a positive seal may be effected.

Another object is to provide a device of this character wherein the seal may be readily broken when it is desired to open the container to which the sealing means is attached.

Another object is to provide a device of this character having means for locking the seal.

A still further object is to provide a device of this character of simple and durable construction and of low manufacturing cost.

Numerous other objects and advantages of this invention will be apparent as it is better understood from the following description, which, taken in connection with the accompanying drawing, discloses a preferred embodiment thereof.

Referring to the drawing:

Figure 1 is a vertical sectional view through the sealing means attached to the top of a glass jar with the valve-like stopper loosely received in the opening of the cover so that air may be exhausted from the jar.

Figure 2 is a vertical sectional view through the sealing means attached to the top of a glass jar showing the stopper after same has been pressed downwardly into the opening of the cover to form a secure seal with the shoulder of the stopper locked below the rim of the flange of the opening.

Figure 3 is a plan view of the device.

Figure 4 is a side elevational view of the stopper.

Figure 5 is an end elevational view of the same.

Figure 6 is an under plan view of the stopper.

Referring more particularly to the drawing, 55 which illustrates a preferred embodiment of the

invention, reference numeral 10 indicates a jar, the top portion only of which is shown. The upper end of the jar is threaded and a metal cover 11 is screwed thereon. In Figure 1 the cover is screwed lightly onto the top of the jar. 5 Two annular seals of rubber or other suitable material are provided, numbered 12 and 13 respectively, between the jar and the cover. The cover 11 is shown screwed tightly onto the jar in Figure 2 wherein the seals 12 and 13 are compressed between the cover and the jar. While two annular rubber seals are shown, either one or the other may be used separately if desired. The cover 11 is provided with a central opening having a downwardly and inwardly inclined 15 flange 14. Within the opening there is a stopper 15 of rubber or other suitable material, the sides of said stopper tapering downwardly and inwardly at substantially the same angle as the flange 14 of the cover. The lower end of the 20 stopper is provided with outwardly or laterally extending arms 16 to limit the outward or upward movement thereof and spaced upwardly of said arms there is an annular shoulder 17 on the stopper. 25

Any suitable vacuum pump means may be employed to evacuate the air from the jar and during the evacuating process the shoulder 17 of the stopper is above the lower end of the flange 14 so that the stopper may freely rise and fall 30 to act as a valve, the shoulder seating on the inner surface of the flange to prevent air returning into the jar. After the air is exhausted from the jar the stopper is pressed inwardly or downwardly until the shoulder 17 thereof is below the 35 lower end of the flange which it engages to form a secure seal as shown in Figure 2.

To break the seal the stopper is pulled upwardly until the shoulder 17 is disengaged from the lower end of the flange and thereby permitting the air to enter the jar. The cover may be then readily unscrewed from the jar. 40

It is thought that the invention and many of its attendant advantages will be understood from the foregoing description and it will be apparent 45 that various changes may be made in the form, construction, and arrangement of the parts without departing from the spirit and scope of the invention or sacrificing all of its material advantages, the form hereinbefore described being 50 merely a preferred embodiment thereof.

Having thus described my invention what I claim is:

1. In a device of the class described, the combination of a container, a cover secured thereon 55

and having an opening therein, a downwardly and inwardly inclined flange about the opening, a tapered stopper adapted to be operatively received in the flanged opening, outwardly extending arms on said stopper adjacent the inner end thereof, and a shoulder about the stopper in upwardly spaced relation to said arms, said shoulder being above the lower edge of the flange during exhaustion of air from the container and adapted to be forced below said lower edge in sealing and locking association therewith after the air has been exhausted from said container.

2. In a device of the class described, the combination of a container having a cover secured thereon, said cover having a flanged opening therein, the flange extending in a downwardly and inward taper, a tapered stopper adapted to be operably received in the flanged opening, means for normally limiting the upward move-

ment of the stopper, and means for sealingly engaging the inner edge of the flange of the cover opening when the stopper is pressed inwardly in said opening, said means being normally above the inner edge of the flange during evacuation of air from the container.

3. In a device of the class described, a vacuum container having an opening therein tapering inwardly from the outer side of said container, a tapered stopper operably received in said opening, laterally extending means on the inner end of the stopper adapted to limit the outward movement of said stopper, and means on said stopper adapted for sealing engagement with the inner edge of the opening when said stopper is fully pressed into said opening, said last mentioned means being normally outside said inner edge of said opening.

CHARLES E. EVANS.
